(57) **CLAIM**

The ornamental design for the button latch for a container, as shown and described.

DESCRIPTION

FIG. 1 is an isometric view of a button latch for a container in accordance with my design;

FIG. 2 is a front, elevation view of the button latch for a container of FIG. 1;

FIG. 3 is a rear, elevation view of the button latch for a container of FIG. 1;

FIG. 4 is a right, side, elevation view of the button latch for a container of FIG. 1;

FIG. 5 is a left, side elevation view of the button latch for a container of FIG. 1;

FIG. 6 is a top view of the button latch for a container of FIG. 1; and,

FIG. 7 is a bottom view of the button latch for a container of FIG. 1.

In the drawings, the broken line showing portions of a button latch depicts environment and forms no part of the claim.

1 Claim, 5 Drawing Sheets
